RADIATOR CORE

Frank A. Neveu, Los Angeles, Calif.

Application April 20, 1935, Serial No. 17,474

6 Claims. (Cl. 257—130)

This invention relates to heat-interchanging devices, and more particularly to radiators of the type commonly used upon automotive vehicles to cool the water used in the circulatory cooling systems thereof.

An object of the present invention is to provide a radiator core construction comprising tube and fin or spacing members arranged in cooperative relationship and provided with novel means 10 for inducing a large amount of turbulence in the many streams of air flowing through the core, without, however, impeding the flow to any material extent, and in this manner effecting an increase in the amount of heat which is transmitted 15 from the tube and fin members to the air.

A more detailed object in this connection is to provide obliquely running beads, preferably of relatively little altitude, in the metal of which the tube members or the fin members, or both of 20 them, are formed, thus causing a multiplicity of shoulders to project from the otherwise relatively smooth walls of the air passages of the core, into the many streams of air flowing therethrough. By so arranging the fin and tube members 25 having these oblique beads therein, that the beads on opposite walls of each air passage are of opposite inclination, a spiral or twisting motion is imparted to each of the air streams, thus inducing the turbulence therein which is so effective in enhancing the capability of the air to absorb heat from the metal against which it impinges. However, the turbulence thus produced is not of such a nature or of such a degree that either the volume or rate of flow of air 30 through the core is seriously interfered with, and this is also a feature which makes for further efficiency of heat dissemination by the core.

It is a still further object of the present invention to adapt the above described principle 40 involving the use of obliquely running beads to the plates of each of the water tube members of a radiator core, in such a manner that a novel type of construction of tube member is provided, which tube member, in addition to being 45 more efficient in cooling, is possessed of advantages in respect of strength and rigidity, and consequently is more durable than water tube members constructed along more conventional lines, and yet which is simple and relatively inexpensive to form and assemble.

The invention possesses other objects and features of advantage, some of which, with those 50 enumerated, will be set forth in the following description of the invention's particular embodiments which are illustrated in the drawings ac-

companying and forming a part of the specification. It is to be understood that I do not limit myself to the showing made by the said drawings and description, as I may adopt variations of the preferred forms within the scope of my invention, as set forth in the claims. 5

Referring to the drawings:

Figure 1 is a perspective view showing a fragment of a radiator core embodying the principles of the present invention. 10

Figure 2 is an enlarged detailed view showing a portion of one of the spacing or radiating fins of Figure 1. 15

Figure 3 is a detailed view in front elevation showing a portion of the structure illustrated in Figure 1, the direction of view being indicated by the arrow 3 of that figure. 20

Figure 4 is a view similar to Figure 1, but illustrating a slightly modified form of my invention. 25

In terms of broad inclusion, the present invention contemplates the improvement of a radiator core in the form of a multiplicity of shoulders formed in the metal parts of the core, which shoulders extend obliquely with respect to the direction of flow of air through the core and project, preferably for a relatively short distance into the streams of air. Moreover, the shoulders thus provided upon opposite sides of each of the many air streams are at opposite angularity, i. e., if the shoulders on one side of an air stream slope toward the rear of the radiator and downwards, those on the opposite side of that same air stream slope towards the rear and upwards, the result being that although the shoulders project for such a short distance into the air stream 30 that the volume and/or rate of flow is not interfered with to any material extent, these obliquely disposed shoulders impart a spiral or twisting motion to each of the air streams, and thus have been found to induce a degree of turbulence 35 to the air streams, resulting in an increased efficiency of heat absorption by the air from the metal parts of the core. 40

Preferably these oblique shoulders are provided through the expedient of relatively shallow beads or channels pressed into the metal of which the core elements are formed. These beads or channels are preferably so small that they do not interfere with the deforming of the metal to the desired shape to produce whichever of the 45 constituent elements of the core is being manufactured, i. e., each of the fin or spacing members may be constructed according to any preferred design, but should carry the additional feature of the oblique shoulders which enhance 50 55

the efficiency of that selected design in the manner mentioned hereinabove.

For example, Figure 1 shows my invention embodied in a radiator core 11 of well known design, which core 11 comprises a plurality of water tube members 12 disposed in spaced parallel relation to provide air spaces 13 therebetween, and preferably a plurality of spacing fins 14 interposed between each two adjacent tube members 12. Each of these tube members 12 comprises a pair of juxtaposed plates 16 and 17 having corrugations 18 extending transversely thereof. The corrugations 18 of both plates 16 and 17 rest into each other at both ends of the 15 corrugations, i. e., along both longitudinal edges 19 of the plates 16 and 17. However, those corrugations 18 of each plate, the crests of which point toward and fit into the valleys between crests of the other plate, are flattened as at 21, 20 these flattened portions, however, being shorter than the width of the plates so that where these crests are not flattened, they fit snugly into and make water-tight connection with a concave portion or valley of the cooperating plate. These 25 flattened portions 21 of both plates 16 and 17 cooperate to define a water passage 22 as clearly shown on Figures 1 and 3, through which water can flow longitudinally of the radiator, i. e., from one header tank to the other, these header 30 tanks not being illustrated.

As a result of this construction, each of the water tube members 12 is in the form of a corrugated strip of metal of double thickness, the two thicknesses being closely adjacent each other 35 at the forward and after faces of the core but being spaced from each other intermediate the edges to define the water passage 22.

The form of fin 14 usually adopted for use in conjunction with tube member 12 is a strip 40 of metal corresponding in width to the water tubes and having corrugations 26 extending transversely thereof, these corrugations 26 preferably corresponding in general shape and size to the corrugations 18 which are formed in the 45 tube members 12. Preferably a plurality of such fins 14 are interposed between each two adjacent tube members and are so arranged that the crests 27 of each fin abut against the crests of the member immediately there adjacent. In this 50 manner, a multiplicity of substantially tubular air cells 27 extending transversely through the core 11 are formed, each of these air cells being defined by the hollow sides of the corrugations of the two associated members, which members 55 may be either two adjacent fin members 14, or a fin member 14 and the tube member 12 there adjacent.

The present invention contemplates improving the efficiency of core constructions by deforming 60 the metal of which the fins 14 and tube members 12 are formed, in addition to the formation of the corrugations hereinabove described. This additional deformation consists of providing obliquely running shoulders 31 which project into the air 65 cells 27 so as to engage the streams of air flowing therethrough. These shoulders 31 can consequently be provided by forming relatively small corrugations 32 in the metal of which the fin and/or tube members are later to be formed, these corrugations extending obliquely, as best 70 shown upon Figures 2 and 3. Preferably, however, the corrugations 32 are smaller than the corrugations 18 and 26, which determine the principal position of the characteristic shape of 75 the tube and fin members 12 and 14, respectively.

Because of the relatively slight height of these corrugations 32 and the shoulders 31 thus presented by the crests of these minor corrugations 32, they interfere to a relatively slight extent with the flow of air through the air passages 27. However, they project far enough into the air passages to cause a material proportion of the air of each air stream to impinge thereagainst and be deflected from its normally straight course through the core either upwards or downwards, 10 depending upon the direction of the shoulder 31 with which it comes in contact. Moreover the parts are so arranged that the shoulders 31 on one side of each passage 27 are of an angularity opposite to that of the shoulders on the opposite side of that air passage; that is to say, if the shoulders 31 on one side of a certain air passage 27 incline toward the after face of the core and upwards, then the shoulders 31 on the opposite side of that same air cell incline toward the after 20 face of the core and downwards. This is most easily accomplished when assembling the core by selecting the constituent elements thereof so that each alternate strip of metal, whether it be a fin, or one of the plates of a tube member, has the 25 shoulders 31 thereof of opposite angularity from that of the shoulders 31 of the element previously placed in the assembly.

Consequently, in each of the air streams traversing the core, those portions of the air stream on one side thereof have a downward motion imparted thereto as they move toward the rear of the core, whereas, those portions of air on the opposite side of that air stream have an upward motion imparted thereto. This induces a spiral 35 or twisting motion to each of the many air streams, which has been found to break up the otherwise smooth flow of the air through the core to an extent which materially increases the capability of the moving air to absorb from the 40 walls of the tube members 12 and from the radiating fins 14, it being understood, of course, that these metal parts of the core have absorbed heat from the water flowing through the water passages 22, in accordance with conventional practice. 45

Figure 4 shows a modified form of my invention in the form of a core 41, the spacing fins 42 of which are preferably similar to those of the previously described modification. Whereas, by a 50 single spacing fin 42 is shown interposed between each two adjacent tube members 43, it should be understood that a plurality of fins could be employed in each air space 44 if desired. Each of the water tube members 43 of this modification 55 comprises a pair of opposed plates 46 and 47 flat and in abutment with each other along their forward and after edges 48 and 49, respectively, by having beads or corrugations 51 projecting outwards from their outer faces intermediate the 60 edges 48 and 49. The corrugations 51 of the two plates 46 and 47 are of opposite angularity, the result being that the hollows or valleys 52 defined by the concave side of each corrugation 51, of each of the plates intersect the hollows 52 of the associated plate. In this manner, the water flowing between the two plates 46 and 47 is divided into several relatively small streams, each of which must pursue a zig-zag course as it flows longitudinally of the core. This course is zig-zag in 65 two directions, i. e., first toward the front and then toward the rear of the radiator, and so on, and also first toward one side and then toward the other side of the radiator, and so on, because each particle of water must first flow into a valley 70 75

52 in one of the plates 46, moving as it does so toward one side of the radiator, and after it has entered that valley 52 being deflected toward the rear of the core. Then that particle must enter 5 a valley 52 of the other plate, requiring that the particle move toward the other side of the radiator, and then after entering that valley, being deflected toward the front of the core. This tortuous course through which each particle of 10 water is required to flow results in positive impingement of each particle many times against the side walls of the passage, thereby insuring the transmission of the maximum amount of heat which the water carries, to the metal of the core. 15 Whereas, Figure 4 illustrates the plates 46 and 47, so constructed that the bases 56 between corrugations 51 are substantially in line with the flat edges 48 and 49, thereby causing abutment of the two plates 46 and 47, not only along the straight 20 edges 48 and 49, but also wherever the bases 56 of one plate intersect those of the other, it should be understood that the bases 56 might be set out slightly from the plane of the flat edges of the associated plate, thereby separating the bases of 25 one plate slightly from those of the other plate and increasing to a material extent the capacity of each water tube member, without seriously interfering with the tortuous nature of the path which each particle of water is required to pursue 30 as it traverses one of the water passages. Moreover, corresponding plates, say the plates 46, of all tube members should have their corrugations 51 of the same angularity, in the event that but a single spacing fin 42 is employed between each 35 two adjacent tube members. This will result in the same advantageous arrangement of oblique shoulders extending through the air cells 61, wherein the shoulders on one side of each air cell are of opposite angularity from those on the opposite side of that air cell. This causes the air 40 stream in each air cell to have the spiral motion.

I claim:

1. In a radiator, a heat-transferring core comprising a plurality of water tube members spaced apart to define air passages therebetween, and fin members disposed in said passages and corrugated transversely to divide said passages into a plurality of air cells, the corrugations of each of said members having obliquely running beads protruding from the walls thereof and the beads of each two adjacent members being oppositely inclined whereby the beads upon opposite walls of each of said cells impart a spiral motion to air moving therethrough.

2. In a radiator core, a plurality of tube members, and spacing fin disposed between each two adjacent tube members and corrugated to define a plurality of air passages in each space between tube members, and means on said tube members and fin presenting obliquely running shoulders projecting into said air passages, the shoulders on opposite sides of each passage being of opposite angularity whereby a spiral motion is imparted to the stream of air traversing each passage. 10

3. In a radiator core, a plurality of plates disposed in spaced, parallel relation, to define fluid passages therebetween, said plates having two sets of deformations therein, one of said sets comprising corrugations extending transversely of said plates, and the other of said sets comprising beads formed in the walls of said corrugations and extending obliquely with respect thereto. 15

4. In a radiator core, a plurality of plates disposed in spaced, parallel relation, to define fluid passages therebetween, said plates having two sets of deformations therein, one of said sets comprising corrugations extending transversely of said plates, and the other of said sets comprising beads formed in the walls of said corrugations 20 and extending obliquely with respect thereto, the beads on opposite sides of each of said fluid passages being oppositely inclined whereby a spiral motion is imparted to fluid moving through said 25 passages. 30

5. In a radiator core, means providing water passages and means providing air passages extending thereacross, said means being of corrugated form to provide a cellular construction with the cells thereof presenting said air passages and the walls of the corrugations defining said cells having beads protruding into said cells and extending obliquely with respect to the longitudinal axes of said cells to impart turbulence to air traversing said cells. 35

6. In a radiator core, means providing water passages and means providing air passages extending thereacross, said means being of corrugated form to provide a cellular construction with the cells thereof presenting said air passages, 45 and the walls of the corrugations defining said cells having beads protruding into said cells and extending obliquely with respect to the longitudinal axes of said cells and the beads on opposite sides of each of said cells being of opposite inclination to impart a spiral motion to air traversing the cells. 50
